(57) CLAIM

I claim the ornamental design of a putting head, as shown and described.

DESCRIPTION

FIG. 1 is a perspective view of a putting head according to the present design;

FIG. 2 is a front view of the putting head of FIG. 1;

FIG. 3 is a left side view of the putting head of FIG. 1;

FIG. 4 is a right side view of the putting head of FIG. 1;

FIG. 5 is a back view of the putting head of FIG. 1;

FIG. 6 is a top plan view of the putting head of FIG. 1;

FIG. 7 is a bottom plan view of the putting head of FIG. 1, FIG. 8 is a perspective view of a putting head according to a variant of the present design;

FIG. 9 is a front view of the putting head of FIG. 8;

FIG. 10 is a left side view of the putting head of FIG. 8;

FIG. 11 is a right side view of the putting head of FIG. 8;

FIG. 12 is a back view of the putting head of FIG. 8;

FIG. 13 is a top plan view of the putting head of FIG. 8; and,

FIG. 14 is a bottom plan view of the putting head of FIG. 8. The broken lines in the figures are for illustrative purposes only and form no part of the claimed design.
